(57) **CLAIM**

(21) Appl. No.: **29/253,656**

The ornamental design for a circular multi-station vending machine, as shown and described.

(22) Filed: **Feb. 9, 2006**

DESCRIPTION

(51) **LOC (8) Cl.** **20-01**

FIG. 1 is a perspective view of a circular multi-station vending machine, showing my new design.

(52) **U.S. Cl.** **D20/7**

FIG. 2 is a front elevational view of the vending machine as seen from a position counterclockwise sixty degrees from the position in FIG. 1.

(58) **Field of Classification Search** D20/1–9,

FIG. 4 is a rear elevational view of the vending machine as seen from a position one hundred eighty degrees from the position in FIG. 1, the rear elevational view being identical to other side elevational views of the vending machine as seen from positions sixty degrees from the position of FIG. 2.

FIG. 5 is a top plan view of the vending machine of FIG. 2. FIG. 6 is a bottom plan view of the vending machine of FIG. 4.

FIG. 7 is a perspective view of a second embodiment of the circular multi-station vending machine, showing my new design.

FIG. 8 is a front elevational view of the vending machine as seen from a position forty-five degrees from the position in FIG. 7, the front elevational view being identical to opposite side and rear elevational views of the vending machine.

FIG. 9 is a top plan view of the vending machine of FIG. 8; and,

FIG. 10 is a bottom plan view of the vending machine of FIG. 8.
